MILL LAYOUT

Edward C. Peterson, Douglassville, and William H. Boblitz, Shillington, Pa., assignors to Birdsboro Corporation, Birdsboro, Pa., a corporation of Pennsylvania
Filed Nov. 13, 1962, Ser. No. 236,845
9 Claims. (Cl. 72—230)

The present invention relates to mill layouts for metal rolling mills.

A purpose of the invention is to increase the flexibility in operating a metal rolling mill.

A further purpose is to permit installation of the equipment of a metal rolling mill in stages, so that a reasonable degree of utility can be obtained with a minimum of equipment at the beginning and greater utility can be secured with a minimum of additional equipment and employing double or conjoint use of as much of the equipment as possible.

A further purpose is to reduce the time in changing the rolls when changing from one product to another in metal rolling mills.

A further purpose is to provide a roughing mill which discharges to a first mill table in line with the roughing mill, which in turn discharges to a continuous mill in prolongation of the first mill table, which in turn feeds the inlet to a looping finishing mill which has a finishing stand in line with and feeding to a second mill table which connects to a cooling bed, and then to provide a lateral transfer from the first mill table to feed an intermediate roll stand which is in line with the finishing stand of the looping finishing mill and also in line with the second mill table.

A further purpose is to provide a second roughing mill stand which will cooperate with the lateral transfer and the intermediate mill stand.

A further purpose is to employ an intermediate mill which is larger than the finishing stand of the looping finishing mill and to replace the finishing stand of the looping finishing mill with a larger mill stand at the same position.

A further purpose is to use a continuous finishing mill which has both a horizontal mill stand and a vertical edger.

A further purpose is to make one or more repeaters and guides of the looping finishing mill slide out of the way to permit the stock from the continuous finishing mill to enter the finishing stand of the looping finishing mill.

Further purposes appear in the specification and in the claims.

In the drawings I have chosen to illustrate one only of the numerous embodiments in which the invention may appear, selecting the form shown from the standpoints of convenience in illustration, satisfactory operation and clear demonstration of the principles involved.

FIGURES 1 and 1a comprise a first set of drawings, FIGURES 2 and 2a comprise a second set of drawings, and FIGURES 3, 3a and 3b comprise a third set of drawings.

FIGURE 1 is a fragmentary plan mill layout showing the first form of the rolling mill of the invention, illustrating the portion of the mill to the left in the first set of drawings.

FIGURE 1a is a fragmentary plan mill layout of the first form which shows the portion of the mill at the right of the portion shown in FIGURE 1 of the first set of drawings.

FIGURE 2 is a fragmentary plan mill layout showing the second form of the installation of the mill of the invention, illustrating the portion of the mill to the left in the second set of drawings.

FIGURE 2a is a fragmentary plan mill layout showing

the portion of the mill of the second form to the right of that shown in FIGURE 2 in the second set of drawings.

FIGURE 3 is a fragmentary plan mill layout showing the third form of installation of the mill of the invention, the view illustrating the portion of the mill to the left of the third set of drawings.

FIGURE 3a is a plan mill layout showing the third form of the installation of the mill equipment, and illustrating the portion of the equipment in the center of the third set of drawings, FIGURE 3a being to the right of FIGURE 3.

FIGURE 3b is a plan mill layout showing the third form of installation of the mill equipment, the portion shown being to the right of that illustrated in FIGURE 3a in the third set of drawings.

FIGURE 4 is a plan view showing an alternate layout for the looping finishing mill.

Because of the large capital invested, many rolling mills find it difficult to expand to produce a diversified product line. Many of the existing mill layouts are objectionable because the layouts are not flexible as to the production of different types of rolled stock. One of the advantages of the invention is to give a wide diversity of types of stock which can be produced.

Also many of the prior art rolling mills are not effective from the standpoint of utilization of mill equipment when changing from one type of product to another. In such prior art mills a large proportion of the total equipment is inactive when a limited number of product lines are being produced. The present invention is concerned particularly with making double or conjoint use of equipment wherever possible.

In some of the prior art mill layouts, it is necessary to stop all operation when changing rolls or adjusting guides. One of the advantages of the present mill layout is that a substantial amount of roll changing or guide changing can be accomplished while bypassing the mill stands on which roll changing is taking place, and at the same time continuing to produce useful products from the mill.

According to the invention, the customer in buying the mill, need make only a minimum initial expenditure and still he obtains a useful, basic mill. By two additional steps, the capabilities of the mill can be increased, both as to product, types, and size of rolled stock.

In the basic mill of form 1, a roughing mill stand discharges on a mill table to an intermediate continuous mill, which in turn feeds a looping finishing mill discharging to a second mill table which feeds a cooling bed.

In the second step, advantage is taken of the lateral zig-zag configuration of the looping finishing mill to permit the installation of a lateral transfer device from the first run-in table, and a continuous finishing mill is fed by the lateral transfer device which utilizes the position of the finishing stand of the looping finishing mill, the repeater being slid out of the way. Thus it is possible to roll on the lateral transfer and the continuous finishing mill while changing rolls on the intermediate continuous mill and on the early mill stands of the looping finishing mill.

In the third form of installation of equipment, a second roughing mill stand is introduced and the number of stands of the intermediate continuous mill desirably increased. As a desirable feature also coiling equipment is installed in the third step.

Referring now particularly to the first form of installation as shown in FIGURES 1 and 1a, billets are loaded on loading skids 20 and discharged by feeding mechanism 21 into the paths of double pushers 22 of a double slide billet heating furnace 23 well known in the art.

At the outlet end of the furnace the billets now heated to hot rolling temperature are discharged by billet ejector

24 on to run-in table 25 and past billet turnaround 26 all well known in the art.

Run-in table 25 feeds the billet to roughing rolling mill stand 26' driven in well known manner by motor 27 and speed reducer 28 under the control of an operator in pulpit 30. The roughing mill is suitably of the three-high type and has a tilting or lift table 31 as well known in the art.

The roughing mill stand 26' discharges the stock to mill table 32 which is sometimes referred to herein as the "first" mill table, past cropping shear 33 to mill stands 34, 35 and 36 of a continuous mill positioned in straight line relation and driven by motor 37 and speed reducer 38 through individual pinion stands 40 to the respective roll stands.

As shown, the motor and the speed reducer desirably have reserve capacity which will be utilized in expanding the equipment of the continuous mill.

The stock passes to looping finishing mill 41 of a character in itself well known in the art, which suitably has a first roll stand 42, a second roll stand 43, a third roll stand 44 and a finishing roll stand 45 which are suitably connected by a transfer guide 46, a first escapement repeater 47, a first inlet guide 48, a second transfer guide 50, a second escapement repeater 51, a second inlet guide 52, a third transfer guide 53, a third escapement repeater 54, a third inlet guide 55, a fourth transfer guide 56, a final escapement repeater 57, a fourth inlet guide 58 and a mill table 60 to a flying shear 61. The mill table 60 is sometimes called the "second" mill table.

For reasons which will later be more clearly set forth, the repeater 57 is mounted to move laterally out of the way on tracks 62 so that it can remain in operative position as shown in FIGURE 1a or be shifted so as to uncover the inlet side of finishing mill 45. For this purpose fourth inlet guide 58 is also mounted on track 63 so that it will move to the side along with repeater 57 when they are to be displaced. Such track moving repeaters are in themselves well known in the art.

The mills will be driven in any suitable manner of which FIGURE 1a shows a suitable indication.

A motor 80 drives speed reducer 81 which in turn drives the mill stands 42, 43 and 44. Likewise, a motor 82, preferably an adjustable speed type, combined with a speed reducer drives finishing mill stand 45.

The mill table 60 feeds, by suitable kickoff means as are well known, to cooling bed 83, and from the cooling bed the stock is taken by mill table 84 through cold bar shear 85 to cradles 86 as well known.

It will be evident that the mill layout of FIGURES 1 and 1a is a completely operative mill which is capable of producing many products.

Using an 18 inch three high roughing stand and a 12 inch intermediate continuous mill having three stands and a looping finishing mill having four stands, typical products are as follows:

Products

Rebars: $\frac{3}{8}$ ", $\frac{1}{2}$ ", $\frac{5}{8}$ ", $\frac{3}{4}$ ", $\frac{7}{8}$ ", 1", $1\frac{1}{8}$ ", $1\frac{1}{4}$ " $1\frac{3}{8}$ "

Angles: $\frac{3}{4}$ " x $\frac{3}{4}$ " x $\frac{1}{8}$ ", 1" x 1" x $\frac{1}{8}$ ", $1\frac{1}{2}$ " x $1\frac{1}{2}$ " x $\frac{1}{8}$ ", $1\frac{1}{2}$ " x $1\frac{1}{2}$ " x $\frac{1}{8}$ ", $1\frac{3}{4}$ " x $1\frac{3}{4}$ " x $\frac{1}{8}$ ", 2" x $2\frac{1}{2}$ " x $\frac{1}{8}$ "

Flats: $\frac{3}{4}$ " x $\frac{1}{4}$ ", 1" x $\frac{1}{4}$ ", $1\frac{1}{4}$ " x $\frac{1}{4}$ ", $1\frac{1}{2}$ " x $\frac{1}{4}$ ", $1\frac{3}{4}$ " x $\frac{1}{4}$ ", 2" x $\frac{1}{4}$ ", $2\frac{1}{2}$ " x $\frac{1}{4}$ ", $3\frac{1}{2}$ " x $\frac{1}{4}$ ", $3\frac{1}{2}$ " x 1", 4" x $\frac{1}{4}$ ", 4" x 1"

Channels: 2" U @ 1.78#

Rounds: $\frac{3}{8}$ ", $\frac{1}{2}$ ", $\frac{5}{8}$ ", $\frac{3}{4}$ ", $\frac{7}{8}$ ", 1", $1\frac{1}{8}$ ", $1\frac{1}{4}$ ", $1\frac{3}{8}$ ", $1\frac{1}{2}$ "

The second step in the expansion of the mill layout of the invention contemplates the provision of alternate means for shortcircuiting the intermediate continuous mill and the looping finishing mill through another mill which can operate while roll changing or other adjustments are accomplished on the intermediate continuous mill and the looping finishing mill.

Thus, as shown in FIGURES 2 and 2a there is no 75

change in the heating furnace setup or in the roughing mill.

A lateral transfer device 87, well known in the art, has been provided from mill table 32 to a new mill table 88 which is in line with and behind mill table 60 before described. The lateral transfer device 87 is capable of transferring the stock laterally from mill table 32 to mill table 88.

In prolongation of mill table 88 is placed continuous finishing roll stand 100, which is driven from motor 101 and speed reducer 102. The continuous finishing roll stand 100 is suitably of horizontal type and is supplemented to complete the continuous finishing mill by vertical edger 103 driven by adjustable speed motor 104 and speed reducer 105. The mill table continues between the continuous finishing roll stand 100 and the vertical edger 103 and beyond the vertical edger 103.

The repeater 57 and the inlet guide 58 move together to the side out of the way and inlet guide 106 connected thereto moves with them into the path of the stock coming from vertical edger 103 to finishing roll stand 45.

In the preferred embodiment of FIGURE 2a, the continuous finishing mill stand 100 is of larger capacity than the finishing mill stand as used with the looping finishing mill so as to permit finishing material of larger cross sectional area and dimensions than possible with the final roll stand of the looping finishing mill. Thus, if the finishing stand 45 when used with the looping finishing mill is a 10" finishing stand, the horizontal mill stand 100 and the vertical edger 103 for the continuous finishing mill will conveniently be 14" mills. Then in order to get the most out of the finishing stand of the looping finishing mill the 10" finishing stand 45 is conveniently replaced by a 14" finishing stand when the continuous finishing mill is used, and which may be fitted with appropriate rolls and guides prior to the interchange.

Thus there are two alternate procedures available in FIGURES 2 and 2a. The stock may for example pass through a 12" intermediate continuous mill and a 10" looping finishing mill, or it may pass through a 14" continuous finishing mill with a 14" finishing stand in place of the final stand of the looping finishing mill. In the latter case the types of products which can be made will differ somewhat from those which can be made from the continuous mill plus the looping finishing mill. Examples of the product line from the intermediate continuous finishing mill and the finishing stand of the looping finishing mill using an 18", three-high roughing stand and 14" mill where required, a 14" vertical mill where required, a 12" intermediate continuous mill, and a looping finishing mill having four stands, are as follows:

Product

Rebars: $\frac{3}{8}$ ", $\frac{1}{2}$ ", $\frac{5}{8}$ ", $\frac{3}{4}$ ", $\frac{7}{8}$ ", 1", $1\frac{1}{8}$ ", $1\frac{1}{4}$ "

Angles: $\frac{3}{4}$ " x $\frac{3}{4}$ " x $\frac{1}{8}$ ", 1" x $1\frac{1}{8}$ ", $1\frac{1}{4}$ " x $1\frac{1}{4}$ " x $\frac{1}{8}$ ", $1\frac{1}{2}$ " x $1\frac{1}{2}$ " x $\frac{1}{8}$ ", $1\frac{3}{4}$ " x $1\frac{3}{4}$ " x $\frac{1}{8}$ ", 2" x $2\frac{1}{2}$ " x $\frac{1}{8}$ "

Channels: 2" U @ 1.78

Flats: $\frac{3}{4}$ " x $\frac{1}{4}$ ", 1" x $\frac{1}{4}$ ", $1\frac{1}{4}$ " x $\frac{1}{4}$ ", $1\frac{1}{2}$ " x $\frac{1}{4}$ ", $1\frac{3}{4}$ " x $\frac{1}{4}$ ", 2" x $\frac{1}{4}$ ", $2\frac{1}{2}$ " x $\frac{1}{4}$ ", $3\frac{1}{2}$ " x $\frac{1}{4}$ ", $3\frac{1}{2}$ " x 1", 4" x $\frac{1}{4}$ ", 4" x 1", 5" x $\frac{1}{4}$ ", 5" x 1"

Rounds: $\frac{3}{8}$ ", $\frac{1}{2}$ ", $\frac{5}{8}$ ", $\frac{3}{4}$ ", $\frac{7}{8}$ ", 1", $1\frac{1}{8}$ ", $1\frac{1}{4}$ ", $1\frac{3}{8}$ ", $1\frac{1}{2}$ ", $1\frac{5}{8}$ ", $1\frac{3}{4}$ ", $1\frac{7}{8}$ ", 2", $2\frac{1}{4}$ "

It will be noted that in making this change-over it is only necessary to change from the 10" to the 14" finishing stand in the looping finishing mill, by bringing in a new roll stand by the crane.

The mill layout of the invention can be further expanded as shown in FIGURES 3, 3a and 3b.

In this instance the heating equipment remains the same but an additional roughing mill stand 120 has been added, connected to an additional speed reducer 121

driven by motor 27, and bar turners have been introduced at 122, 123 and 124. This permits a more rapid breakdown of the billet, or starting with larger billets, as desired.

In FIGURE 3a the intermediate continuous mill has been expanded to introduce an additional mill stand 125 driven from the same speed reducer 38, with corresponding shortening of mill table 32.

Optional coiling equipment 126 has been added including coilers 127 to permit taking off coilable rod directly beyond the flying shear 61.

By taking form as shown in FIGURES 2 and 2a, it will be possible to change much more quickly from one product to another, since the continuous finishing mill can be used while the intermediate continuous mill and the remainder of the looping finishing mill are undergoing roll changing or other modifications.

Finally, the additional roughing stand and the additional continuous mill stand of the form shown in FIGURES 3, 3a and 3b will permit the use of larger billets or the production of smaller rolls from the same size billets.

If the coilers are added, then of course coiled rod can be produced.

In some cases it will be more convenient to set up the looping finishing mill with the individual mill stands in line—rather than in staggered relation—as shown in FIGURE 4, driving from motors and speed reducers 81' and 82' at the opposite sides of the looping finishing mill, motor 82' preferably being an adjustable speed type. In other cases, it may be convenient to eliminate the three or four stand intermediate continuous mill.

In view of our invention and disclosure, variations and modifications to meet individual whim or particular need will doubtless become evident to others skilled in the art, to obtain all or part of the benefits of my invention without copying the structure shown, and we, therefore, claim all such insofar as they fall within the reasonable spirit and scope of my claims.

Having thus described my invention what we claim as new and desire to secure by Letters Patent is:

1. In a rolling mill layout, a roughing mill, a first mill table receiving the stock from the roughing mill, a first finishing mill with inlet in prolongation of the first mill table receiving the stock from the first mill table, and having a finishing mill stand laterally displaced from the inlet and receiving the stock passing through the first finishing mill, a second mill table receiving the output from the finishing mill stand of the first finishing mill, in combination with a lateral transfer device receiving the stock from the first mill table and transferring the stock laterally before the stock enters the first finishing mill, and a continuous finishing mill receiving the stock from the lateral transfer device and discharging the stock to the second mill table.

2. A mill layout of claim 1, in which the continuous finishing mill is of larger capacity than the finishing mill stand of the first finishing mill, in combination with a substitute finishing mill stand for the first finishing mill which receives the stock from the continuous finishing mill and discharges the stock to the second mill table.

3. A mill layout of claim 1, in which the continuous finishing mill is of larger capacity than the finishing stand of the first finishing mill.

4. A mill layout of claim 1, in which the continuous finishing mill comprises a horizontal mill stand and a vertical edger.

5. A mill layout of claim 1, in which the first finishing mill is a looping mill and has a repeater ahead of the finishing stand, in combination with slide means for moving the repeater out of the path from the continuous finishing mill to the finishing stand.

6. A mill layout of claim 5, in which the first finishing mill has an inlet guide between the repeater and the finishing stand, said inlet guide moving with said slide means when the repeater moves out of the path between the continuous finishing mill and said finishing stand.

7. A mill layout of claim 6, in combination with an auxiliary guide moving with said slide means interposed between said continuous finishing mill and said finishing stand when said repeater moves out of said path.

8. A mill layout of claim 1, in combination with an additional roughing mill stand on said roughing mill.

9. In a rolling mill layout, a roughing mill, a first mill table in prolongation of the roughing mill, a first finishing mill with inlet in prolongation of the first mill table for receiving the stock from the first mill table, a looping finishing mill having an inlet from the outlet side of the first finishing mill and having a finishing mill stand laterally displaced from the inlet and receiving the stock passing through the first finishing mill, a second mill table receiving the output from the finishing stand of the first finishing mill, in combination with a lateral transfer device receiving the stock from the first mill table and transferring the stock laterally before the stock enters the first finishing mill and before it enters the looping finishing mill, and a continuous finishing mill receiving the stock from the lateral transfer device and discharging the stock to the second mill table.
